GRINDING MACHINE

Edward Schottland, Forest Hills, N. Y., assignor
of one-half to Robert Schottland, Jackson
Heights, N. Y.

Application January 28, 1943, Serial No. 473,798

11 Claims.

(Cl. 51—103)

This invention relates to improvements in grinding machines and more particularly it pertains to machines for grinding the edges of circular plates and similar objects.

One specific use to which the invention has been specifically adapted is for the grinding of the peripheral edges of circular plates of glass in the manufacture of mirrors and other articles formed from glass plates circular in form.

It is one object of the invention to provide a machine which will operate simultaneously on more than two articles.

It is a further object of the invention to provide a device which may be employed in connection with a grinding wheel of the type commonly employed for finishing the edges of rectangular plates of glass.

It is a still further object of the invention so to construct the machine that the time required to produce the finished edge upon the article being treated may be considerably reduced as compared with machines at present in use with which I am familiar.

Other objects of the invention will appear as the nature thereof is better understood for which purpose reference will now be had to the accompanying drawings and the following specification.

In the drawings,

Figure 1 is a top plane view of the machine constructed in accordance with the present invention;

Figure 2 is a transverse vertical sectional view thereof taken substantially on the line 2—2 of Figure 1;

Figure 3 is a view in end elevation looking at the right hand end of the machine as illustrated in Figure 1;

Figure 4 is a detail sectional view on an enlarged scale taken substantially on the line 4—4 of Figure 2, and;

Figure 5 is a view in side elevation illustrating a slightly modified form of the invention.

Referring to the drawings by reference character, the machine includes a suitable supporting base or frame 10, having legs 11 and feet 12 supporting the same. Carried by the base 10 there is a housing 13, having an opening 14 in the top wall 15 thereof.

Mounted in the base 10 in suitable bearings there is a grinding wheel 21, the peripheral edge of which projects through the opening 14 in the top wall 15 of the housing 13, heretofore mentioned, and this grinding wheel 21 is driven preferably by a belt 22 and a motor 23, the belt 22

passing around a pulley 24 carried by the shaft 25 upon which the grinding wheel is mounted.

Water or other suitable liquid is admitted to the housing by means of a spray nozzle or the like 26, and carried off from the grinding wheel housing by pipes 26'.

As heretofore stated, the grinding wheel is of a conventional type having a plurality of spaced grooves formed in its peripheral edge which extend entirely around the grinding wheel. This grinding wheel being of the conventional type forms no part of the present invention except in combination with those features alleged to be new.

The reference numeral 50 designates a rigid frame which comprises two side members 51 and 52 connected together in spaced relation by a plurality of braces or cross members 53, see Figure 1. This frame may be formed as an integral part of the base, heretofore mentioned, and is supported above the same and above the grinding wheel by four extensions, there being two extensions 16 on the right hand side of the machine and two extensions 17 on the left hand side thereof.

Depending from the left hand edge of each of the side members 52 of the frame 50, there is an extension 54 which is provided with an elongated slot 55. Adjustably mounted on each of these extensions 54 there is a bar or the like 56 and bolts 57 are employed to secure the bars or members 56 in an adjustable position vertically of the frame 50.

Referring to Figure 3, it will be noted that a shaft 58 is mounted in the upper end of the bars or members 56 which is secured in position therein by means of a nut or the like 59. This shaft 58 extends forwardly of the machine and two spaced levers 60 are pivotally mounted thereon and held in spaced relation by means of a sleeve 61 interposed between the levers. The free ends of the levers 60 are connected by a cross member or the like 62.

As best illustrated in Figure 2, each of these levers 60 is provided with an elongated slot 63 and adjustably mounted in these slots between the levers 60 there is a roller 64. As best illustrated in Figure 3, this roller 64 has a plurality of peripheral grooves 65, the specific purpose of which will be hereinafter described.

The reference character 27 designates a rectangular frame comprising two side members 28 connected by one or more transverse members 29. This frame is pivotally mounted on the shaft 22 which is suitably mounted in bearings carried

by the left hand extensions 17, heretofore mentioned. The shaft 30, see Figure 1, carries upon its rear end a driving pulley 31, its forward end being extended beyond the side member 52 of the frame 50. Carried at the forward end of the shaft 30 and secured thereto by means of a nut or the like 32, there is a roller 33 which is provided with a plurality of spaced grooves 34, the purpose of which will be hereinafter more specifically described.

The construction just described is illustrated in detail in Figure 4, the roller 33 being secured to the reduced extension 35 of the shaft 30 by means of a nut 35.

The frame 27 heretofore mentioned, is provided in its left hand end with a bearing 36 which receives the shaft 30, and this construction forms the means by which the frame 27 may be pivotally mounted within the frame 50 as best illustrated in Figures 1 and 2.

Each of the side members 28 of the frame 27 is provided with an elongated slot 37 and adjustable along these slots there is a shaft 38 which has its forward end extending beyond the side member 52 of the frame 50 as best illustrated in Figure 1. Mounted upon the forward extension of the shaft 38 there is a roller 39 which is provided with a plurality of spaced grooves 40, the purpose of which will be hereinafter specifically described.

Connected to the cross member 62 of the levers 60 by a hook or the like 41 there is a coil spring 42, the lower end of which is attached to a link or the like pivotally connected as at 44 to a foot treadle 45. This foot treadle 45 is connected for engagement and disengagement with a yielding spring actuated toothed bar 46 pivotally mounted as at 48 by means of which the foot treadle 45 may be held in adjustable position thereby to place the spring 42 under desired tension. The foot treadle 45 is pivotally mounted upon the base 10 as at 47.

Mounted at the outer ends of the side members 28 of the frame 27, there is a cross bar and as best illustrated in Figure 3 of the drawings, there are two springs 71 which are connected at their lower ends as at 72 to the cross bar 70, the upper ends of the springs being connected as at 73 to one of the cross members 53 of the frame 50.

The reference character A designates the circular plates to be operated upon, herein illustrated as plates of glass, the edges of which are to be finished by grinding. In the present instance, there are six of these plates shown and the manner in which the grinding of the edges of these plates is simultaneously carried out will now be described.

The several rollers 33, 39 and 64 are so supported that the grooves in each roller will align with the corresponding grooves in each of the other rollers and with the corresponding grooves in the grinding wheel.

The roller 33 constitutes a fixed point and the pulley 31 carried upon the shaft to which this roller is attached is driven by means of a belt or the like 80 in a manner which will be herein-after described.

The plates A, the edges of which are to be ground, are supported by the fixed roller 33 and the roller 39 carried by the frame 27. Under normal conditions, the plates, the lever 27, and the lever 60 are moved in a direction away from the grinding wheel by the tension of the springs 71 which tend to rock the rigid frame 27 out-

wardly about its pivotal point upon the shaft 30, these springs having sufficient tension so to support the plates in such position.

To position the plates it will be understood that the foot treadle 45 is released to permit of the lifting of the frame 50 to place the plates upon the rollers 33 and 39.

After the plates have been positioned, the frame 50 is lowered to the point where its roller 64 will engage the plates, after which the foot treadle is depressed to place the spring 42 under sufficient tension to move the edges of the plates into position within their respective grooves in the peripheral edge of the grinding wheel 21 in grinding contact with said grinding wheel.

In the preferred form of the invention, the grinding wheel would be continuously operating in the direction indicated by the arrow B. The belt 80, heretofore mentioned, is driven by means of a pulley 81 carried upon a shaft 82 to which is connected a gear 83 which meshes with a driving gear 84 carried by the shaft 25 of the motor, and thus it will be seen that the belt 80 will be driven in the direction of the arrow C, operating the driving pulley 31, the shaft 30 and the roller 33 which constitutes a driving roller for the plates, driving them in a direction opposite to that of the rotation of the grinding wheel 21.

From the foregoing, it will be apparent that the frame by reason of the fact that it is pivotally mounted upon the shaft 30 and the fact that the springs 71 tend to move the frame away from the grinding wheel and the spring 42 tends to overcome the tension of the springs 71 maintaining the plates A in engagement with the grinding wheel, the several plates are yieldingly mounted with respect to the grinding wheel, and are yieldingly supported by the rollers 33 and 39 and held yieldingly in engagement with said supporting rollers 33 and 39 by the roller 64.

The supporting rollers 33 and 39 engage the circular plates at spaced points below their centers while the roller 64 engages the plates at a point above the center, thus providing a three point engagement with the plates to insure their proper positioning with respect to the grinding wheel.

After the edges of the plates have been sufficiently ground, they may be removed and finished by buffing or any other desired conventional method.

In the modified form of the invention illustrated in Figure 5 of the drawings, the plates A are illustrated as being supported upon two rollers 90 and 91 and held in engagement therewith by means of a roller 92.

In this type of device, the roller 91 which constitutes a driving and supporting roller for the plates, is mounted on a shaft 94 mounted in suitable bearings supported by the frame 93. This roller is driven by a belt 95 from any suitable source of power, not shown.

The rollers 90 and 92 are carried by a frame-like element 96 which is pivotally mounted upon the shaft 94. This frame-like member is provided with an elongated slot 97 in which the roller 90 may be adjusted and it has an up-standing arm 98 which is slotted as at 99. Slidably mounted in the slot 99 of the arm 98 there is a block 100 and the roller 92, heretofore mentioned, is rotatably mounted upon said block. Connected to the block 100 as at 101 there is a coil spring 102 which is also connected to the frame-like member 96 as at 103.

In said figure, the reference character 104 designates a grinding wheel and the plates A, in operation are adapted to rest within the grooves of the grinding wheel, it being understood that it is the same type of wheel as described in connection with the preferred form of the invention.

Connected to the pivoted frame-like member 96 as at 105 there is a coil spring 106 which is also connected as at 107 to the supporting frame 93. This spring is under tension and tends normally to move the plates A in a direction away from the grinding wheel 104.

Means is provided, however, for maintaining engagement of the plates with the grinding wheel and this means may constitute either a spring or a weight, not shown, connected as at 108 to the pivoted frame-like member 96 and exerting its force in the direction of the arrow 109 against the tension of the spring 106.

From the foregoing, it will be apparent that in this modified form of the invention the plates to be operated upon are supported by the rollers 90 and 91 and are retained in engagement therewith in a yielding manner by means of the tension supplied by the spring 102 upon the roller 92.

Furthermore, it will be noted that, by reason of the pivotal mounting of the frame-like member 96, the tension provided by the spring 106 and the force applied thereto in the direction of the arrow 109, said frame-like member is also yieldingly mounted with respect to the grinding wheel 104.

In this form of the invention it is to be understood that the several rollers 90, 91 and 92 will be provided with a plurality of circumferential grooves to receive a plurality of plates as in the preferred form of the invention.

From the foregoing, it will be apparent that the present invention provides a machine for grinding the peripheral edges of circular plates in which a comparatively large number of plates may be operated upon simultaneously and in which, by reason of the fact that the plates are rotated in a direction opposite to the direction of the rotation of the grinding wheel, the operation is expeditiously and effectively carried out.

After having thus described the invention, what is claimed as new is:

1. In a machine for grinding the peripheral edge of a circular plate, a grinding element, a driving roller having engagement with the peripheral edge of a circular plate to be ground, a supporting roller having engagement with the peripheral edge of said plate at a point spaced with respect to the point of engagement of the driving roller, a pressure roller engaging the peripheral edge of said circular plate and adapted to urge the same into engagement with the driving roller and the supporting roller, and in grinding contact with the grinding element, means for exerting pressure upon said pressure roller, and means for driving the driving roller.

2. In a machine for grinding the peripheral edge of a circular plate, a rotating grinding wheel, means for rotating the grinding wheel, a frame, a fixed position plate supporting and driving roller carried by the frame, a lever pivotally mounted on said frame, a plate supporting roller carried by the lever, said rollers having engagement with the peripheral edge of a circular plate to be ground at spaced points upon one side of the center of said plate, means tending normally to move the pivoted lever in a direction away from the grinding element thereby to move the peripheral edge of a plate to be ground out of

grinding contact with the grinding element, means for rotating the supporting and driving roller thereby to rotate the plate, and means for applying a yielding pressure to the plate to retain its peripheral edge in grinding contact with the grinding element.

3. In a machine for grinding the peripheral edge of a circular plate, a rotating grinding wheel means for rotating the grinding wheel, a frame,

10 a fixed position plate supporting and driving roller carried by the frame, a lever pivotally mounted on said frame, a plate supporting roller carried by the lever, said rollers having engagement with the peripheral edge of a circular plate

15 to be ground at spaced points upon one side of the center of said plate, means tending normally to move the pivoted lever in a direction away from the grinding element thereby to move the peripheral edge of a plate to be ground out of

20 grinding contact with the grinding element, means for rotating the supporting and driving roller thereby to rotate the plate, and means for applying a yielding pressure to the plate to retain its peripheral edge in grinding contact with the grinding element,

25 said last mentioned means including a roller having engagement with the peripheral edge of the plate being ground at a point upon the opposite side of the center of the plate from those points of engagement of said

30 plate by the supporting and driving roller and the said supporting roller, and means for applying pressure to said pressure roller.

4. A machine for grinding the peripheral edges of circulating glass plates comprising in combination,

35 a rotating grinding wheel, a frame, a lever pivotally mounted on said frame, a glass plate supporting roller carried by said lever, a spring connected to the frame and to the lever and tending to move the lever in a direction away from the grinding element, a fixed position supporting and driving roller mounted upon the frame and co-operating with the first mentioned roller to support a circular glass plate with its peripheral

40 edge in grinding contact with the grinding wheel, a second lever pivotally mounted upon the frame, a pressure roller carried by said second pivoted lever and adapted for engagement with the peripheral edge of the glass plate to be ground

45 in opposition to said aforementioned rollers to hold the glass plate in position, yielding means acting in opposition to said first mentioned spring for moving the glass plate to position with its peripheral edge in grinding contact with the

50 grinding wheel, and means for driving said driving and supporting roller.

5. In a machine of the type described in combination, a supporting frame, a grinding wheel, a combined plate driving and supporting roller

60 carried by the supporting frame, means for driving said roller, a frame member mounted for pivotal movement about the axis of the combined plate driving and supporting roller, a plate supporting roller carried by said pivotally mounted

65 frame member in spaced relation to the plate driving and supporting roller, a yieldingly mounted plate engaging roller for maintaining a plate in yielding engagement with the plate driving and supporting rollers, a grinding element

70 and means for moving the frame member and a plate carried thereby into engagement with the grinding element.

6. In a machine of the type described in combination, a supporting frame, a grinding wheel, a combined plate driving and supporting roller

carried by the supporting frame, means for driving said roller, a frame member mounted for pivotal movement about the axis of the combined plate driving and supporting roller, a plate supporting roller carried by said pivotally mounted frame member in spaced relation to the plate driving and supporting roller, a yieldingly mounted plate engaging roller for maintaining a plate in yielding engagement with the plate driving and supporting rollers, a grinding element and means for moving the frame member and a plate carried thereby into engagement with the grinding element, said last mentioned means including a resilient member for providing yielding grinding engagement between the plate to be ground and the grinding wheel.

7. In a machine of the type described in combination, a stationary supporting frame, a plate driving and supporting roller carried by said frame, means for driving said roller, a pivoted frame member mounted for pivotal movement about the axis of the driving and supporting roller, a plate supporting roller adjustably mounted on the pivoted frame in spaced relation to said plate driving and supporting roller, a third roller slidably mounted on the pivoted frame and movable into engagement with a plate supported upon the two first mentioned rollers, means for moving the slidably mounted roller into engagement with a plate for yieldingly retaining the plate in engagement with the supporting and driving roller and the supporting roller, a grinding wheel, and means for retaining the plate carried by the pivoted frame in grinding contact with the grinding wheel.

8. In a machine of the type described in combination, a stationary supporting frame, a plate driving and supporting roller carried by said frame, means for driving said roller, a pivoted frame member mounted for pivotal movement about the axis of the driving and supporting roller, a plate supporting roller adjustably mounted on the pivoted frame in spaced relation to said plate driving and supporting roller, a third roller slidably mounted on the pivoted frame and movable into engagement with a plate supported upon the two first mentioned rollers, means for moving the slidably mounted roller into engagement with a plate for yieldingly retaining the plate in engagement with the supporting and driving roller and the supporting roller, a grinding wheel, and means for retaining the plate carried by the pivoted frame in grinding contact with the grinding wheel, said last mentioned means including means tending normally to move the pivoted frame in a direction away from the grinding wheel and means for moving the pivoted frame in the direction of the grinding wheel in opposition thereto.

9. In a machine of the type described in combination, a stationary supporting frame, a plate

driving and supporting roller carried by said frame, means for driving said roller, a pivoted frame member mounted for pivotal movement about the axis of the driving and supporting roller, a plate supporting roller adjustably mounted on the pivoted frame in spaced relation to said plate driving and supporting roller, a third roller slidably mounted on the pivoted frame and movable into engagement with a plate supported upon the two first mentioned rollers, means for moving the slidably mounted roller into engagement with a plate for yieldingly retaining the plate in engagement with the supporting and driving roller and the supporting roller, a grinding wheel, and means for retaining the plate carried by the pivoted frame in grinding contact with the grinding wheel, said last mentioned means including a coil spring connected at one end to the pivoted frame for moving the pivoted frame in a direction away from the grinding wheel, and means for moving the pivoted frame in the direction of the grinding wheel in opposition to the force of said spring.

10. In a machine of the type described in combination, a stationary supporting frame, a plate driving and supporting roller carried by said frame, means for driving said roller, a pivoted frame member mounted for pivotal movement about the axis of the driving and supporting roller, a plate supporting roller adjustably mounted upon the pivoted frame in spaced relation to said plate driving and supporting roller, a grinding wheel, a coil spring connected at one end to the stationary frame and at its other end to the pivoted frame for normally supporting the pivoted frame in a position to support a plate carried thereby out of contact with the grinding wheel, a lever pivotally and adjustably mounted on the stationary frame, a plate engaging roller carried by said pivoted lever and means for rocking the pivoted lever about its pivotal point to retain a plate in operative position in the pivoted frame upon the driving and supporting roller and the supporting roller aforementioned, said means also serving to move the pivoted frame in the direction of the grinding wheel to bring a plate carried thereby into operative engagement with the grinding wheel.

11. In a machine for grinding the peripheral edge of a circular plate, a grinding element, a driving roller having engagement with the peripheral edge of a circular plate to be ground, a supporting roller having engagement with the peripheral edge of said plate, a pressure roller engaging the peripheral edge of said circular plate and in grinding contact with the grinding element, means for exerting pressure upon said pressure roller, and means for driving the driving roller.

EDWARD SCHOTTLAND.
